SNUBBED TRUCK

Filed July 30, 1959

to friction wall 52 of the shoe by a pair of parallel generally vertically extending spaced side walls 64. To accommodate insertion of a tool, in order to facilitate assembly of the device in a conventional manner, side walls 64 may be provided with holes 66 (FIGURE 1) which are disposed for alignment with holes 68 in the related transverse walls 28 of the bolster.

Also formed integrally with and extending inwardly from the inner side of each of the shoe friction walls 52 is spring wall 70. The wall 70 may be also connected to the friction wall 52 by a pair of spaced vertical ribs 72. As best seen in FIGURE 1, spring wall 70 presents on its inner side, or the side toward the shoe wedge wall 60, a spring seat 74 having extending therefrom a boss 76 disposed for alignment with boss 44 presented on the related spring seat 42 of the bolster.

Again referring to FIGURE 1, it will be seen that the wedge and spring walls of the shoe diverge from the friction wall 52 of the shoe approximately at right angles to each other so as to form angles of less than 90° with the friction wall of the shoe.

Still referring to FIGURE 1, it will be seen that each shoe is disposed in the bolster pocket with the main body of the shoe positioned outwardly of the bolster wedge wall and with only the spring wall of the shoe extending inwardly of the bolster wedge wall. Actuation of the shoe is achieved by means of a coil compression spring 80 which is compressibly interposed between the spring seats 42 and 74 of the bolster and friction shoe, respectively, with the spring seat bosses 44 and 76 received within the end coils of the spring to maintain it in proper alignment.

Thus it will be understood that each friction shoe is positioned with both of its faces being disposed on one side of the bolster wedge wall while the shoe actuating spring is disposed on the opposite side of the bolster wedge wall, with the compressional axis of the spring disposed to extend generally parallel to the wedge surface of the bolster and to the wedge face of the shoe.

I claim:

1. In a snubbed railway car truck the combination of: a side frame having spaced columns presenting mutually opposing vertical friction surfaces defining an opening therebetween; a bolster resiliently supported on said side frame for vertical movement in said opening, said bolster having pockets on opposite sides thereof and having in each of said pockets a wedge wall sloping upwardly toward the adjacent side frame column surface; friction shoes disposed in respective pockets and movable vertically therein, each of said shoes having a vertical friction wall presenting an outer friction face engaging the friction surface of the related side frame column and having extending from said friction wall a pair of inwardly diverging walls, one of said diverging walls being a wedge wall presenting an inwardly facing wedge face engaging an outwardly facing wedge surface of the related bolster wedge wall, and the other of said diverging walls being a spring wall extending inwardly of and normal to the related bolster wedge wall; and a spring disposed in said pocket inwardly of the related bolster wedge wall and compressibly interposed between and directly abutting a spring seat on the bolster within the bolster pocket and a spring seat on the friction shoe spring wall, said spring being the sole member reacting between said bolster and friction shoe and disposed so that its reaction axis has a vertical component of direction and the spring being operable to urge the friction shoe vertically and to urge the faces thereof into engagement with the related wedge and friction surfaces of the bolster and side frame column.

2. In a snubbed railway car truck the combination of: a side frame presenting a vertical friction surface; a bolster resiliently supported on the side frame for vertical movement relative thereto and having at a side

thereof adjacent said surface a pocket having therein a wedge wall presenting a wedge surface sloping upwardly toward and facing said side frame surface; a friction shoe disposed in and movable vertically in said bolster pocket, said shoe having a vertical friction wall presenting an outwardly facing friction face engageable with said side frame friction surface and having extending from said friction wall a pair of inwardly diverging walls, one of said diverging walls being a wedge wall presenting an inwardly facing wedge face engageable with said bolster wedge wall surface, the other of said diverging walls being a spring wall extending inwardly of said bolster wedge wall; and a spring located inwardly of said bolster wedge wall and reacting between and directly abutting a spring seat in the bolster pocket and a spring seat on said friction shoe spring wall, said spring being the sole member reacting between said bolster and friction shoe and disposed so that its reaction axis has a vertical component of direction and the spring being thereby operable to urge the friction shoe vertically and to urge said shoe friction and wedge faces into engagement with the friction and wedge surfaces of the side frame and bolster, respectively.

3. In a snubbed railway car truck, the combination of: a side frame presenting a vertical friction surface; a bolster resiliently supported on the side frame for vertical movement relative thereto, said bolster having adjacent said surface a pocket presenting therein a wedge surface sloping upwardly and outwardly toward and facing said side frame friction surface; a friction shoe disposed within and movable vertically in said pocket and having inwardly facing and outwardly facing diverging wedge and friction faces engageable with the wedge and friction surfaces of the bolster and side frame, respectively; and a spring disposed inwardly of said bolster wedge surface and reacting between the bolster and the shoe, and constituting the sole means so reacting, to urge the faces of the shoe into engagement with the related surfaces of the bolster and side frame, the reaction axis of said spring being parallel to said bolster wedge surface and having a vertical component of direction.

4. In a snubbed railway car truck, the combination of: a side frame presenting a vertical friction surface; a bolster resiliently supported on the side frame for vertical movement adjacent said friction surface, said bolster having a pocket and presenting in said pocket a wedge surface sloping toward and facing said side frame friction surface; a friction shoe disposed in and movable vertically in said pocket having one portion interposed between said surfaces and presenting diverging faces engageable with the respective bolster and side frame surfaces, said shoe having another portion extending inwardly beyond said bolster surface; and spring means in said pocket located inwardly of said bolster surface and directly engaging the bolster and said other portion of the shoe, said spring means being the sole member reacting between said bolster and friction shoe and disposed so that its reaction axis has a vertical component of direction and the spring means being thereby operable to urge the friction shoe upwardly and to urge the shoe faces into engagement with the related bolster and side frame surfaces.

5. In a snubbed railway car truck, the combination of: a side frame member presenting a friction surface; a bolster member resiliently supported on the side frame member and presenting a friction surface facing and angularly related to said side frame member surface; a vertically movable friction shoe having one portion interposed between said surfaces and presenting a pair of angularly related faces engageable with respective surfaces of the bolster and side frame members, said shoe having another portion extending beyond the surface of one of said members; and resilient means located on the opposite side of the surface of said one member from

said one portion of the shoe and interposed between and directly engaging and reacting between said one member and said other portion of the shoe, said resilient means constituting the sole means so reacting, and being arranged so that its reaction axis has a vertical component of direction and being thereby operable to urge the friction shoe upwardly and to urge the shoe faces into frictional engagement with the surfaces of the respective members.

6. In a snubbed railway car truck, the combination of: 10 a side frame member presenting a friction surface; a vertically movable bolster member presenting a friction surface facing and angularly related to said side frame member surface; a vertically movable friction shoe presenting a pair of angularly related friction faces located between said surfaces for respective engagement therewith; and resilient means carried by one of said members and positioned on the side of the surface of said one member remote from the shoe and reacting between and directly engaging said one member and said shoe, said resilient means constituting the sole means so reacting, and being arranged so that its reaction axis has a vertical component of direction and being thereby operable to urge the friction shoe upwardly and to urge the shoe faces into engagement with the surfaces of the respective members.

7. A snubbed railway car truck according to claim 6, wherein said one member has a pocket therein, and wherein said shoe, said resilient means, and the friction surface of said one member are located within said pocket.

8. A snubbed railway car truck according to claim 7, wherein said one member has a wall in said pocket and wherein the friction surface of said one member is on said wall.

9. A snubbed railway car truck according to claim 7, wherein said pocket is in the bolster member.

10

5

10. A snubbed railway car truck according to claim 7, wherein the surface of the other of said members is substantially vertical and wherein the surface of said one member is inclined relative to the vertical, and wherein the compressional axis of said resilient means is substantially parallel to the surface of said one member.

11. A snubbed railway car truck according to claim 7, wherein one face of the shoe and an engaging surface of one of the members are V-shaped.

15

20

12. A friction shoe for a snubbed truck arrangement, comprising: a friction wall presenting on one side thereof a friction face; and a pair of walls formed integrally with said friction wall and extending from the opposite side thereof, said walls diverging from said friction wall, one of said diverging walls being a wedge wall presenting a wedge face facing away from said friction wall, the other of said walls being a spring wall presenting on the side thereof toward said wedge wall a spring seat, said spring seat and the face of said wedge wall defining intersecting planes which are normal to each other.

25

30

13. A bolster for a snubbed truck arrangement, comprising: spaced horizontal top and bottom walls connected by spaced vertical walls and defining therewith a pocket; an inclined wedge wall in said pocket extending from one of said top and bottom walls, said wedge wall presenting on its outer side a friction surface; and a spring seat in said pocket located inwardly of said wedge wall on the opposite side of said wedge wall from said surface, said spring seat and said wedge wall surface defining intersecting planes which are normal to each other.
